[57] CLAIM

The ornamental design for a guitar vibrato assembly, as shown and described.

DESCRIPTION

FIG. 1 is a top plan view of a guitar vibrato assembly showing my new design;

FIG. 2 is a bottom plan view thereof;

FIG. 3 is a front elevational view thereof;

FIG. 4 is a rear elevational view thereof;

FIG. 5 is a top, front and side perspective view thereof;

FIG. 6 is a top, rear and side perspective view thereof;

FIG. 7 is a right side view of the design as seen from FIG. 1;

FIG. 8 is a left side view of the design as seen from FIG. 1;

FIG. 9 is a top perspective view thereof;

FIG. 10 is an enlarged partially exploded left side perspective view of the vibrato collar member shown for clarity of illustration; and,

FIG. 11 is an enlarged partially exploded, left side perspective view of the vibrato handle member shown for clarity of illustration.
